UNITED STATES PATENT OFFICE.

WILLIAM G. SLAUSON, OF OLEAN, NEW YORK.

PRINTER'S LOCK-UP AND FURNITURE.

SPECIFICATION forming part of Letters Patent No. 638,072, dated November 28, 1899.

Application filed March 15, 1899. Serial No. 709,149. (No model.)

To all whom it may concern:

Be it known that I, WILLIAM G. SLAUSON, a citizen of the United States, residing at Olean, in the county of Cattaraugus and State of New York, have invented certain new and useful Improvements in Printers' Lock-Ups and Furniture, of which the following is a specification, reference being had therein to the accompanying drawings.

10 This invention relates to telescopic lock-ups for printers' use.

The object of the invention is to produce a lock-up device which may be quickly applied to the bed of a cylinder-press to lock up a small chase thereon or a chase smaller than the press-bed.

15 The present invention is also particularly adapted for use in locking up a small form in a large chase without entirely filling the chase with furniture.

Usually when a small chase with printing-form in it is placed on a press-bed and does not entirely fill it the remaining space is filled out either by an empty chase or with blocks of 20 wood or metal or with strips of wooden furniture, which requires considerable time. Moreover, the material used for filling these spaces is liable to spring up in locking it up on account of unevenness or too much pressure, causing 25 loss of time, and often it works up while the press is running, blacking or smutting the sheets of paper, causing not only loss of time, but waste of material. Further, the material usually used has to be "justified" or 30 made to fill the opening exactly or with so much fullness that when a locking device, which is either a quoin or the clamp of the press worked with a wrench, is applied the filling material and chase will be firmly locked 35 and held in place. Then some time is consumed in applying the quoin or tightening the screws of the clamp. Similarly when a small form of type or other printing material is placed in a large chase the chase is filled 40 out with wooden or metallic furniture, practically filling the space in the chase not occupied by the form, and then quoins have to be applied, after the filling has been "justified," in order to lock the form in the chase 45 securely for lifting and printing. Wooden furniture is liable to shrinking and swelling as well as to wear, which make it uneven

and uncertain in a lock-up or form. When a form is left on the bed of a press over night or a chase is set away for future use which has 55 wooden furniture in it, the swelling is liable to make the lock-up too tight and "spring" the form or lock-up, and likewise the shrinking of the wooden material is liable to loosen the lock-up and cause the form to fall out of the 60 chase into "pi" or, on a press-bed, to cause printing "out of register" or pulling of type from the form. Metallic blocks are heavy and metallic furniture both heavy and expensive and considerable time is used in filling, justifying, and locking a form with it, and the labor of transporting heavy forms is not inconsiderable. The weight of heavy 65 forms filled with heavy furniture requires added power and expense of running the press. 70 Sometimes an empty chase is used to fill an open space in a large chase with a small form in it or to fill a space between a small chase and the clamps or sides of a press-bed; but in the use of a chase for filling space justifying is again necessary, and as chases are 75 usually made for use to contain printing-forms they are seldom true on the outside and other material has to be used with them in order to secure straight edges and secure 80 bearing-surfaces. The telescopic lock-up which I have devised overcomes these objections in a great measure and, combining, as it does, a furniture filling any space without requiring justification and a quick quoin for 85 locking, it saves a large share of the time usually consumed in locking up small forms in large chases or small chases on large press-beds. Besides, my lock-up is more reliable 90 than the ordinary furniture.

Figure 1 is a plan of a lock-up according to this invention. Fig. 2 is a plan of the same in extended position. Fig. 3 is a broken plan of the lock-up, showing extension-quoin; and Fig. 4 is a plan of the snail by which the quoin 95 is extended. Fig. 5 is a partial section and partial elevation showing quoin and snail and the extension-catch at the top of the lock-up. Fig. 6 is an elevation of the key or wrench by which the snail is operated.

The outer tube of the telescopic lock-up consists of a flat-sided straight rectangular tube of metal, preferably open at both ends. For convenience this tube has a slot A' in its

upper surface and has a notch or opening A² either in its edge, as shown in Figs. 1 and 2, or in its upper surface, as indicated in Fig. 5. A toothed catch B works through this opening, the catch being pressed inwardly by a spring C, which is connected to the tube A and to the catch by rivets or in other usual manner. The vertical height of the tubular piece A is less than the height of the type or stone ordinarily used. The width varies according to the requirements.

Inside the tube A, I place a second rectangular metallic tube D, which fits neatly, but not tightly, in the said tube A and is preferably of equal length. One side or face of this tube D is notched, as indicated at D', Fig. 2. The teeth D' are preferably inclined in the opposite direction from the teeth of catch B, so that the teeth may act as ratchet-teeth and permit the movement of tube D in one direction by the inclines on the teeth lifting the catch, as common in ratchet engagement. Thus the interior tube D may be forced or drawn out of the tube A with no resistance except the friction of the surfaces, including the ratchet-teeth; but to return tube D within the tube A the catch B must be lifted out of engagement with teeth D'. Any suitable stop may be used to prevent the complete removal of the tube D from tube A, if desirable to keep the tubes permanently together. Usually the fit is such that the parts will remain together under ordinary usage.

It is preferable that catch B be near the end of tube A to permit full extension of the tube D; but, as will readily appear, it is not material to the extension which side of the interior tube contains the ratchet-teeth. For some purposes it is advisable to place catch B on the upper surface of the furniture, so that the piece A is free from projection at its edges and can be used as an ordinary filler.

Inside one end of tube D, I place the extension-quoin K. This quoin, as shown, has side bars K' and curved ribs K² on its upper surface. The bars K' serve to guide the quoin in tube D and ribs K² serve for engagement with the snail.

An abutment-piece L is secured inside tube D as by rivets passing through the abutment-piece and tube. This piece L has curved ribs L'.

A disk or snail M, having a spiral thread on one of its faces, is placed in the tube D in position to have its spiral thread M' engage the curved ribs L' and K². Disk or snail M has a hole M² for application of a wrench, and tube D has a perforation through which the wrench, as O, may enter said disk. The slot A' in tube A permits the entrance of the key or wrench when the telescopic tubes are closed.

When the parts are assembled as in Fig. 5, the quoin being drawn inward, it will appear that the rotation of snail M will cause the spiral thread M' to engage ribs L' K², and as the ribs L' are fixed such rotation in one di-

rection must cause the disk to move along, and as the snail at the same time engages ribs K² these ribs and quoin K must move to a greater extent. The snail M thus forms a means for advancing and retracting the quoin K.

The lock-up is usually applied on a press-bed by laying it down in the place to be filled and extending it till both ends touch, when the turning of the key and tightening of the quoin will lock up the chase securely. To lock up a form in a chase, the operation is the same. The lock-up is removed by turning the locking-key in the reverse direction.

A pair of lock-ups will usually lock a chase on a press-bed or a form in a chase. If a lock-up is needed in more than one side of a form or chase, two pairs will generally suffice.

I provide the lock-ups in sets of different lengths, two or more of the same length, in order to accommodate the varying spaces to be filled.

For locking small stones on the beds of lithographic presses I make the device deeper, so that it may have a better hold on the sides of the stone, which are usually beveled or rounded at the edges. I also face the coin with leather or other pliable material in order to better adapt it to the rough surface and breakable nature of the stone.

By the use of the key provided for tightening the quoin in my device the degree of pressure applied may be more readily graduated than with the screw and wrench ordinarily provided for locking stones on lithographic presses, and breakages of the stone by too much pressure will be with my device less liable than with the ordinary device.

Another advantage of my device over the ordinary way of locking and holding small chases on large press-beds is found in the securing and maintaining of accurate register. Being of metal, there is no squeezing of it into smaller space at one time than another.

In cases where the lock-ups are used between the bearers of a press and the chase on either side the chase may be easily and quickly moved one way or the other as slightly or as much as may be desired for the purpose by slightly loosening the one quoin and tightening the other.

In the United States patent to Guyon, No. 76,440, dated April 7, 1868, a variety of extensible furniture is shown in which a central piece having a T-head is adjustable in direction of its length between parallel bars having notched surfaces. Such furniture, so far as I am aware, has not been largely used in printing-offices, and is objectionable because it is open, irregular, and in parts, which must be detached for every adjustment. I do not claim such furniture.

Snail-disks such as I have described are old and well known for analogous purposes in the mechanical arts, and I have thought it unnecessary to give an extended description of such device.

It will be readily understood that modifications can be made within the limits of my claims without departing from the spirit of the invention; also, that my telescopic furniture may be extended and used with ordinary quoins or closed up and used as in ordinary furniture.

What I claim is—

1. The telescopic lock-up described consisting of a straight rectangular metallic tube, a second straight rectangular metallic tube longitudinally movable within the first, a locking device whereby the inner tube may be fastened in extended position, and a locking-
5 quoin inclosed near one end of the inner tube and having engagement with a snail-disk within the tube, by which said quoin may be projected, substantially as described.
2. In combination with the rectangular me-
tallic tube of the character described, a quoin inclosed in one end of said tube but capable of projection therefrom, said quoin having side guides and a curved rib, a snail-disk en-
gaging said quoin and a curved rib connected
15 to the tube, and means for rotating the snail-
disk, substantially as described.
3. In printers' lock-ups a tubular rectangular metallic piece having a side opening, a snail-disk within the tube and having a key-
seat in position to be reached through said
20 opening, a fixed rib in the tube with which
the spiral rib of the snail engages, and an ex-

tension-quoins provided with curved ribs with which the snail-disk engages, all combined substantially as described.

35

4. In printers' lock-ups, the straight rectangular telescopic tubes, one within the other, the rack on the inner tube, and the pawl on the outer tube engaging said rack through an opening in the outer tube, in combination 40 substantially as described.

5. In printers' lock-ups, the straight rectangular outer metallic tube, the straight rectangular inner tube, and locking means connecting the tubes whereby the inner tube 45 may be inclosed or projected and locked in projected position, and an extensible quoin in the outer end of the inner tube, and means for extending and holding said quoin, all combined substantially as described.

50

6. In printers' lock-ups, the straight rectangular outer metallic tube, the straight rectangular inner tube, and locking means connecting the two, whereby the inner tube may be entirely inclosed, or projected and locked 55 at any position a little less than full extension, substantially as described.

In testimony whereof I affix my signature in presence of two witnesses.

WILLIAM G. SLAUSON.
